UNITED STATES PATENT OFFICE.

CHARLES W. COHN, OF NEW YORK, N. Y.

DISPLAY-CASE.

1,287,639.

Specification of Letters Patent. Patented Dec. 17, 1918.

Application filed January 30, 1914. Serial No. 815,377.

To all whom it may concern:

Be it known that I, CHARLES W. COHN, a citizen of the United States, residing in the borough of Manhattan, city, county, and State of New York, have invented certain new and useful Improvements in Display-Cases, of which the following is a specification.

This invention relates to show or display cases, and is particularly directed to improvements in small or so-called "counter" cases which are generally of elongated rectangular construction. Such cases are particularly adapted for the display of handkerchiefs and other small articles.

The object of the present invention is to provide a showcase, and particularly one of the character just described, which shall be of the greatest simplicity of construction, which may be shipped in flat or knock-down condition, which may be readily assembled by anyone who can use a screw-driver, and which may be easily disassembled and reassembled without the use of a skilled mechanic to replace a broken glass or for the purpose of reshipment.

To this end the invention in its preferred form comprises a bottom and two end boards, the latter being grooved to receive two strips or plates of glass which constitute the front and the top of the case. At the rear the case is provided with a connecting strip between the end boards to which is hung a horizontally hinged door, if desired.

Referring to the drawings which illustrate the preferred form of the invention,

Figure 1 is a front view of the case.

Fig. 2 is a rear view thereof, the door partly broken away.

Fig. 3 is a section on the line 3—3 in Fig. 1, and

Fig. 4 is a section on the line 4—4 in Fig. 2.

Referring to the drawings, let A indicate the case as a whole which, to provide a clear view of the interior for the display of the goods, is provided with a glass front B and a glass top C. The ends D and E are preferably constructed of wood, as is also the bottom board or base F. A door G is provided at the rear and which is mounted upon horizontal hinges H secured to the back strip I.

In the construction of the case the bottom board F constitutes the base of the structure and is adapted to receive the articles to be displayed. The bottom board is preferably grooved at each end as indicated at K to re-

ceive the lower edges of the ends D, E, which tenons L and fitting in the grooves. The presence of the tenons at these edges affords shoulders which extend over the top face of the bottom board as shown at M, thus not only increasing the stiffness of construction, but providing a better finish on the exterior of the case. The ends D and E are shown connected to the bottom board by screws J J, two being used at each end in Fig. 4. The screws preferably pass through the bottom board at the grooves K and enter the end boards at the tenons. Each of the ends is formed on its inner face with a vertical groove N and a horizontal groove O, the grooves being contiguous to the front and top edges of the end boards, as best seen in Fig. 4. The grooves N and O are designed to receive the front and top glasses B and C. The bottom board F may be provided with a longitudinal slot contiguous to its front edge to receive the lower edge of the front glass B, but I have found in practice that this may be permitted to rest on the top surface of the board without disadvantage.

At the rear of the case and along the upper edge of the latter I provide a strip I which is formed with a groove the bottom flange Q of which underlies the rear edge of the top glass C, and supports the latter along its edge so that the glass will be capable of sustaining some considerable load if the latter is inadvertently placed upon it. The front edge of the top glass C is, however, preferably spaced slightly above the edge of the front glass B, as best seen in Fig. 3, so that shocks will not tend to fracture either glass. Preferably the front edge of the top glass C overhangs the front glass, thus producing a better finish. The strip I is fastened to the end boards D and E preferably by screws P, one at each end.

The door G, as before stated, is preferably hinged at its upper part to the strip I and closes downwardly to the position shown in Fig. 3, the bottom board F being preferably formed with a recess R to receive the lower edge of the door when the latter is closed.

The case may conveniently rest upon rubber feet or pads, such as at S, to hold the case slightly elevated above the counter.

In the use of the invention for the display of handkerchiefs I prefer to provide a rack composed of uprights T T, and cross-piece U, the latter bearing a number of slid-

ing holders V adapted to support handkerchiefs in their unfolded condition. The end boards D and E are drilled with holes W adapted to receive the uprights T T.

5 The case thus provided is extremely cheap and simple in construction. At the same time it is attractive in appearance and durable in use. The entire case is held together by a few screws, six being all that are necessary for the purpose. When the parts are 10 disassembled they pack closely together for shipping, and in case of the breakage of one or more of the parts, such as the front or top glass, the case can be repaired quickly 15 by the ordinary person without having to resort to the services of a skilled mechanic.

While I have shown in detail one form of the invention it will be observed that minor changes can be made therein without departing from the invention.

20 I claim as my invention:

1. A knock-down show case having a bottom board, two end boards removably secured thereto by screws, a glass front and a 25 glass top, the end boards having grooves removably receiving the ends of the top and front, the grooves for the top being in such position in the end boards and in such relation to the top edge of the front glass

that the front edge of the top glass when in 30 position therein overhangs the front glass and is spaced slightly above the same, and a strip at the rear of the case connecting the upper sides of the end boards and removably secured thereto by screws. 35

2. A knock-down show case having a bottom board provided with grooves at the ends, two end boards each having a tenon at its lower edge, the tenons respectively being located in the said grooves, and each 40 said end boards having shoulders above said tenons extending over and engaging the top face of the bottom board adjacent the groove, screws passing through the bottom board at the grooves and entering the 45 tenons for removably securing the end boards to the bottom board, a glass front and a glass top removably carried by the end boards, and a strip at the rear of the case connecting the upper edge of the end boards 50 and removably secured thereto by screws.

In witness whereof, I have hereunto signed my name in the presence of two subscribing witnesses.

CHARLES W. COHN.
